GRANT HAMMOND, OF HARTFORD, CONNECTICUT, ASSIGNEE OF ONE-THIRD TO ALVA C. WASHBURN, OF PITTSFIELD, MASSACHUSETTS, AND ONE-THIRD TO FREDERICK G. CRANE, OF DALTON, MASSACHUSETTS.

FIREARM.

1,124,427.

Specification of Letters Patent. Patented Jan. 12, 1915.

Application filed December 11, 1912. Serial No. 736,095.

To all whom it may concern:

Be it known that I, GRANT HAMMOND, a citizen of the United States, and a resident of Hartford, in the county of Hartford and State of Connecticut, have invented a new and Improved Firearm, of which the following is a specification.

My invention relates especially to that class of devices known as "automatic firearms" and an object of my invention, among others, is to provide a device of this class of high power, and one extremely rapid in its operation.

One form of device embodying my invention and in the construction and use of which the objects hereinabove set out, as well as others, may be attained, is illustrated in the accompanying drawings, in which—

20 Figure 1 is a view in side elevation of a pistol embodying my invention, with parts cut away to show construction and the muzzle of the barrel being broken off. Fig. 2 is a detail view of a portion of a pistol embodying my invention, with parts cut in section on plane denoted by dotted lines 2—2 of Fig. 4. Fig. 3 is a top view of my improved pistol with parts broken away to show construction and with the muzzle of 30 the barrel broken off. Fig. 4 is a detail end view, looking from the front, of my improved pistol, the lower part of the stock or handle being broken off. Fig. 5 is a detail top view of the breech-bolt and actuator therefor, with parts broken away to show construction and the bolt being shown in its locked position. Fig. 6 is a side view of the same. Fig. 7 is a view similar to Fig. 6 but with the breech-bolt shown in unlocked position.

40 My invention relates more especially to the mechanism for automatically ejecting the shell and for inserting a cartridge into the barrel, for which reason the details of 45 construction of such mechanism only are shown herein as sufficient for a thorough understanding of the invention, the other mechanisms being of any ordinary construction.

50 In the accompanying drawings the numeral 10 denotes the frame of the pistol supplied with grips 11 constituting the stock, this frame having the usual trigger guard 12, trigger 13, and hammer 14, the

connection between the trigger and hammer 55 being of any desired form of construction. The handle or frame has a recess 15 at its upper forward part and a projection 16 at its upper rear part, said projection 16 having a slot 17.

A receiver 18 is suitably secured to the handle, a projection 19 on the receiver being located in the recess 15, and a rearward projection 20 resting in the slot 17, pins passing through the walls of the slot and recess 65 and through said projections securing and holding the parts together. A magazine opening 21 is formed through the receiver, opening into a breech-bolt chamber 59 having an ejection opening 22. The receiver 70 also has a recess 23 extending from its front part with a reduced threaded opening 24 extending from said recess into the breech-bolt chamber.

A barrel 25 is fitted in the recess 23 and 75 has a reduced threaded end 26 fitting the threaded opening 24. A port 27 extends from the barrel through the receiver and through the wall of an expansion tube 28 secured, as by means of interengaging screw 80 threads, within an expansion tube recess 29 in the front end of the receiver. An expansion sleeve 30 is located on the expansion tube, its end being closed by a closing screw 31. The sleeve 30 has a yoke 32 preferably 85 integrally formed therewith at its inner end and projecting from opposite sides, the arms of the yoke being secured to actuator operating rods 33 extending into breech opening 90 spring chambers 34 containing breech opening springs 35 thrusting at one end thereof against the walls of the chambers and at opposite ends against slotted heads 36 in each of which a latch 37 carrying a trip 38 is pivotally mounted but preferably having 95 some frictional resistance to pivotal movement. The trips 38 travel in slots 39 in the walls of the spring chambers 34 in position to strike trip engaging shoulders 40 constituting the ends of the slots.

100 Actuator operating sleeves 41 are located for reciprocating movement in actuator operating sleeve chambers 42 formed in the receiver 18, each of said sleeves containing a breech closing spring 43, each of which 105 thrusts with one end against a nipple 44 closing the end of its sleeve, each of said springs thrusting with its opposite end

against the shouldered end of a resistance rod 45 located within each sleeve 41 and projecting through the nipple 44, the end of each rod being secured, as by interengaging screw threads, in the end wall of caps 80 abutting against the projections containing the chambers 42. There are two breech opening spring chambers and two breech closing sleeve chambers formed, as to the chambers of each pair, on opposite sides of the receiver, each of said chambers containing the mechanisms above described. Each of the sleeves 41 has a locking bolt opening 46 formed in its end extending laterally thereof and the end of each sleeve is recessed as at 47 to receive the ends of rounded extensions 48 from a breech-bolt actuator 49. This breech-bolt actuator has a hammer recess 50 in its end in which the upper end of the hammer 14 rests when the parts are in their normal position, and actuator arms 51 extend along opposite sides of the breech-bolt 52. A firing pin 53 has one end resting loosely in a hole 54 in the actuator, said pin projecting through the breech-bolt in position to strike the primer of a cartridge located in the breech in position to be fired, the breech-bolt having a limited turning movement between the arms 51 and also on or with said pin, the latter being loosely positioned in the breech-bolt. Studs 55 project one from each arm 51 into cam grooves 56 located in opposite sides of the breech-bolt.

It will be seen from the above description that the actuator together with the firing pin and breech-bolt form a unitary structure, the breech-bolt being supported within and carried by the other members.

The breech-bolt has locking lugs 57 located on opposite sides thereof in position to enter guide grooves 58 (shown in dotted lines in Fig. 1) formed in the wall of the breech-bolt chamber 59 and extending lengthwise thereof. These guide grooves extend into a locking groove 60 extending around the wall of the breech bolt chamber and in which the lugs 57 rest in the normal position of the parts. An ejector groove 61 extends lengthwise along the breech-bolt and within which an ejector 62 extending from a plate 78 secured in the projection 20 projects. An ejector recess 63 opens out of the groove 61 at one end thereof, the groove and recess permitting lengthwise movement of the bolt and also the limited rotary movement thereof, hereinbefore mentioned. The firing pin 53 has a flange 64 forming a shoulder against which a firing pin spring 65 thrusts, the other end of the spring thrusting against the bottom of the spring chamber 66, thus holding the firing pin normally at the rearward limit of its play. A firing pin sleeve 67 fits a screw threaded opening in the breech-bolt, its end being

located in position to receive the flange 64 and limit the rearward movement of the firing pin.

Actuator locking bolts 68 are located in opposite sides of the actuator in position to engage the locking bolt openings 46 in the actuator operating sleeves 41 thus locking the parts together. Finger pieces 69 project from each of the bolts laterally beyond the side of the actuator, inward pressure upon the finger pieces serving to disengage the bolts from the bolt openings 46 and permit the actuator and firing bolt to be withdrawn from the breech-bolt chamber. Locking bolt springs 70, located underneath the bolts and preferably extending into a recess in the finger pieces, serve to press the bolts normally into locked position, retaining pins 71 extending through the actuator and laterally across the finger pieces 69 and recesses 72 therein, serving to hold the locking bolt and finger pieces in position.

An annular groove 73 extends around the breech-bolt, an extractor collar 74 is located in this groove, and an extractor 75 extends forwardly from the collar and has the usual lip to engage the flange of a cartridge shell. As the breech-bolt moves backward after the discharge of the pistol, this extractor draws the shell out of the breech, the lower edge of the shell striking the ejector 62 throwing the shell out through the opening 22 in the usual manner.

The operation of the device is as follows, the parts being in their normal positions as shown in Figs. 1 to 6 of the drawings, excepting that the hammer 14 is cocked, a pull upon the trigger 13 releases the hammer and it is thrown forward by its spring, in a manner well known, striking the firing pin 53 and forcing it against the primer of the cartridge that is exploded thereby, the firing pin moving freely in the actuator, firing pin sleeve, and breech-bolt. As the bullet, that is forced outward by explosion, passes the port 27, expanding gases pass through said port into the expansion tube 28 and acting against the end of the expansion sleeve 30 within the same, forces said sleeve forwardly carrying with it the yoke 32, the actuator operating rods 33 secured to the yoke, and the latches and trips 37 and 38. As the trips 38 encounter the trip shoulders 40 the latches 37 are thrust into position to engage the shoulders of the latch recesses 76 in the sleeves 41 thus locking the rods 33 to the actuator operating sleeves 41. This movement of the rods 33 has compressed the breech opening springs 35 and when the bullet has passed out at the muzzle the gases being free to escape from the expansion tube 28 permits the breech opening springs to exert their force to return the rods to their normal position in which operation the actuator operating sleeves 41 are carried back.

wardly, compressing the breech closing springs 43. As the actuator operating sleeves 41 move backwardly, they carry the breech-bolt actuator 49. As the actuator begins its rearward movement the studs 55 acting in the cam grooves 56 give a partial rotation to the breech bolt, which at this time is locked by the engagement of the locking lugs 57 with the edges of the locking groove 60. When the actuator has carried the studs 55 backward until they engage the opposite end of the grooves 56 the breech-bolt will have been rotated sufficiently to locate the locking lugs opposite the guide grooves 58, at which time the bullet will have passed out of the muzzle of the pistol thus allowing the full force of the gases of explosion to be exerted thereon. The continued movement of the actuator carries the breech-bolt with it, opening the breech chamber and permitting the shell to be ejected as hereinbefore mentioned. The backward movement of the actuator presses the hammer backward, cocking the pistol in the usual manner. In this rearward movement of the actuator operating rods 33 under the force of the springs 35 the trips 38 encounter disengaging shoulders 77 on the receiver, freeing the latches 37 from engagement with the latch recesses 76, permitting the sleeves 41 to be moved by the springs 43 forward to their normal position. In this movement of the sleeves the actuator is carried forward, the lugs 57 traveling along the guide grooves 58 until they enter the locking groove 60, when the action of the studs 55 in the cam grooves 56 gives a partial rotation to the breech bolt securing it in locked position.

I claim—

- 40 1. A firearm including a frame, means to receive a projectile for discharge, firing mechanism mounted in the frame, a member arranged to receive the gases of explosion by which it is operatively moved, said firearm having a breech opening spring chamber with a slot in the side wall thereof, a spring located in said chamber, a latch carried by said member within and along said slot to engage the end thereof for disengaging action, a breech-bolt actuator having a shoulder to be engaged by said latch, means for returning the actuator to its normal position, and a breech-bolt to be operated by said actuator.
- 45 2. A firearm including a frame having a sleeve chamber, means to receive a projectile for discharge, firing mechanism mounted in the frame, a member arranged to receive the gases of explosion by which it is operatively moved, an actuator including a sleeve projecting into a sleeve chamber, a rod secured to the bottom of said chamber and projecting into the sleeve, a spring thrusting with one end against the bottom of the sleeve and
- 50 with the other end against a shoulder on the

rod, means for connecting and disconnecting said member and said sleeve, and a breech-bolt connected to be operated by said actuator.

3. A firearm including a frame having a sleeve chamber, means to receive a projectile for discharge, firing mechanism mounted in the frame, an actuator including a member arranged to receive the gases of explosion by which it is operatively moved, a breech opening spring chamber, a spring located in said chamber to resist the movement of said member, a sleeve projecting into said sleeve chamber, a rod secured to the bottom of said chamber and projecting into the sleeve, a spring thrusting with one end against the bottom of the sleeve and with the other end against a shoulder on the rod, means for connecting and disconnecting said member and sleeve, and a breech-bolt connected to be operated by said actuator.

4. A firearm including a frame, means to receive a projectile for discharge, firing mechanism mounted in the frame, a member arranged to receive the gases of explosion by which it is operatively moved, said firearm having a pair of breech opening spring chambers located one on each side of the frame, a pair of operating sleeve chambers located one on each side of the frame, springs located in the breech opening spring chambers to resist the movement of said member, springs located in the operating sleeve chambers to resist the movement of an actuator, the actuator, means for connecting and disconnecting the actuator to and from said member, and a breech-bolt mounted to be operated by said actuator.

5. A firearm including a frame, means to receive a projectile for discharge, firing mechanism mounted in the frame, a member arranged to receive the gases of explosion by which it is operatively moved, breech opening spring chambers located one on each side of the frame, a yoke extending laterally from said member, rods secured one to each end of the yoke and projecting into said breech opening spring chambers, springs mounted in said chambers and opposing movement of said rods, a latch carried by said rods and having one end projecting into a slot to engage the end thereof, operating sleeve chambers located one on each side of the frame, a rod secured at one end and projecting into each of said chambers, springs located in said chambers to resist the movement of said rods, an actuator arranged with parts to engage and tension said last mentioned springs, and a breech-bolt connected to be operated by said actuator.

6. A firearm including a frame, means to receive a projectile for discharge, firing mechanism mounted in the frame, a member arranged to receive the gases of explosion

by which it is operatively moved, an actuator sleeve projecting into a chamber in the firearm, means for connecting and disconnecting said member with and from said sleeve, an actuator removably secured to said sleeve, and a breech-bolt connected to be operated by said actuator.

7. A firearm including a frame, means to receive a projectile for discharge, firing mechanism mounted in the frame, a member arranged to receive the gases of explosion by which it is operatively moved, actuator sleeves projecting into chambers on opposite sides of the firearm, means for connecting and disconnecting said sleeve to and from said member by which the sleeves are moved in one direction, means for moving the sleeves in the opposite direction, a breech-bolt actuator removably secured to the sleeves, and a breech-bolt operatively connected with the actuator.

8. A firearm including a frame, means to receive a projectile for discharge, firing mechanism mounted in the frame, a member arranged to receive the gases of explosion by which it is operatively moved, actuator sleeves projecting into chambers on each side of the firearm, means for connecting and disconnecting said sleeves with and from said member by which the sleeves are moved in one direction, a spring for moving each of the sleeves in an opposite direction, an actuator including a member having laterally extending bolts to engage extensions from said sleeve, means for actuating the bolt to engage and disengage the members, and a breech-bolt connected to be operated by said actuator.

9. A firearm including a frame, means to receive a projectile for discharge, firing mechanism mounted in the frame, a member arranged to receive the gases of explosion by which it is operatively moved, actuator sleeves projecting into chambers on the opposite sides of the firearm, said sleeves having laterally extending openings in the ends thereof, means for connecting and disconnecting said sleeves with and from said member by means of which the sleeves are moved in one direction, means for moving the sleeves in the opposite direction, an actuator having a member located between the ends of the sleeves, bolts projecting laterally from said member to engage openings in the sleeves, means for operating the bolts, and a breech-bolt carried by the actuator.

10. A firearm including a frame, means to receive a projectile for discharge, firing mechanism mounted in the frame, a member arranged to receive the gases of explosion by which it is operatively moved, actuator sleeves projecting into chambers on opposite sides of the firearm, means for connecting and disconnecting said sleeves and said member for moving the sleeves in one direc-

tion, means for moving the sleeves in the opposite direction, said sleeves having lateral openings at the end thereof, a breech-bolt actuator having a member located between the ends of the sleeves, spring pressed bolts 70 projecting laterally from said members to engage said openings, finger pieces connected with the bolts to move them from disengagement with said openings, and a breech-bolt carried by said actuator.

11. A breech-bolt mechanism for a firearm including a movably mounted breech-bolt actuator, a breech-bolt rotatably mounted in and supported by said actuator, said parts forming a unitary structure removable 80 from the firearm, means for operating the actuator, said breech-bolt having a cam groove, a locking lug mounted on said bolt, and a stud projecting from the actuator into said cam groove.

12. A breech-bolt mechanism for a firearm including a movably mounted breech-bolt actuator having oppositely disposed arms, means for operating the actuator, studs projecting from said arms, a breech-bolt supported and carried by and having cam grooves within which said studs project, and locking lugs located on opposite sides of the breech-bolt.

13. A firearm including a frame, means to receive a projectile for discharge, firing mechanism, a member arranged to receive the gases of explosion by which it is operatively moved, said firearm having a breech-bolt locking groove and a breech-bolt guide 100 groove, a breech-bolt actuator operatively connected with said member, a breech-bolt mounted in and supported by said actuator, said parts constituting a unitary structure removable from the firearm, said breech bolt 105 having a cam groove, a stud projecting from the actuator into said cam groove, and locking lugs projecting from opposite sides of the breech-bolt.

14. A firearm including a frame, means to receive a projectile for discharge, firing mechanism, a member arranged to receive the gases of explosion by which it is operatively moved, a breech-bolt actuator including oppositely disposed arms and studs 115 projecting from said arms, means for operatively connecting said actuator and said member, a breech-bolt rotatably mounted between said arms and having cam grooves into which said studs project, and locking lugs projecting from opposite sides of the breech-bolt.

15. A firearm including a frame, means to receive a projectile for discharge, firing mechanism, a member arranged to receive the gases of explosion by which it is operatively moved, breech-bolt actuating sleeves, means for operatively connecting said sleeves and said member, a breech-bolt actuator, means for removably securing the actu-

ator to said sleeves, said actuator including arms oppositely disposed, a breech-bolt rotatably mounted between said arms and having cam grooves, studs projecting from said arms into said cam grooves, and lugs projecting from opposite sides of the breech-bolt to engage locking and guide grooves in said firearm.

16. A breech-bolt mechanism including a breech-bolt actuator having arms projecting therefrom, means for operating the actuator, a breech-bolt rotatably mounted between said arms and having a cam slot, a stud projecting from an arm into said slot, a collar surrounding the breech-bolt and loosely supported thereon, an extractor secured to said collar, and guide lugs projecting from opposite sides of the breech-bolt to engage a locking groove and a guide groove in said fire-
20 arm.

17. A breech-bolt mechanism for a fire-arm including a breech-bolt actuator having oppositely disposed arms, means for operating the actuator, studs projecting from said arms, a breech-bolt movably mounted between said arms by which it is supported and carried and having cam grooves within which said studs project, and locking lugs located on opposite sides of the breech-bolt.

18. A firearm including a frame, means to receive a projectile for discharge, firing mechanism mounted in the frame, a member to receive the gases of explosion by which it is operatively moved, a yoke secured to
25 said member and projecting to opposite

sides thereof, said firearm having a pair of breech opening spring chambers located one on each side of the frame, an actuator sleeve chamber, an actuator sleeve located in the actuator sleeve chamber, springs located in 40 the breech opening spring chambers to resist the movement of said member, a spring located in the actuator sleeve chamber to resist movement of an actuator, the actuator, means for connecting and disconnecting the 45 actuator and said sleeve, and a breech-bolt mounted to be operated by said actuator.

19. A firearm including a frame, means to receive a projectile for discharge, firing mechanism mounted in the frame, a member 50 arranged to receive the gases of explosion by which it is operatively moved, breech opening spring chambers located one on each side of the frame, a yoke secured to and extending laterally from said member, rods se- 55 cured one to each end of the yoke and projecting into said breech opening spring chambers, springs mounted in said chambers and opposing movement of said rods, an actuator sleeve chamber, an actuator sleeve 60 therein, a spring located therein to resist movement of an actuator, the actuator, means for connecting and disconnecting the actuator sleeve and said spring rods, and a breech-bolt connected to be operated by said 65 actuator.
